Specification of Letters Patent.

Patented Oct. 28, 1919.

Original application filed March 27, 1914, Serial No. 827,565. Divided and this application filed August 5, 1914. Serial No. 855,274.

To all whom it may concern:

Be it known that I, OLIVER M. BABCOCK, a citizen of the United States, residing in Chicago, Cook county, Illinois, have invented an Improvement in Boxes, of which the following description, in connection with the accompanying drawings, is a specification, like characters on the drawings representing like parts.

10 This invention relates to boxes and the like and is intended to provide a novel construction of box blank and box and a method of making the same.

15 This application is a division of application Serial No. 827565; filed March 27, 1914.

Among other objects, the invention is intended to provide a box which shall be simple and economical to manufacture; which shall be susceptible of manufacture 20 upon automatic or partly automatic machinery; and which in the finished box shall be strong and durable and preferably tight.

For purposes of illustration the invention will be described herein as embodied in a 25 flexible sectional box composed of separate cleated side sections connected by binding wires encircling the side sections and secured to the cleats. It is to be understood, however, that the invention is not limited to 30 this specific type of box.

In the drawings, Figure 1, is a side elevation of a finished box blank embodying features of the invention.

Fig. 2 is a perspective showing the box 35 blank of Fig. 1, partly folded.

Fig. 3 is an end elevation of a finished box made from the blank shown in Fig. 1.

The illustrative box blank of Fig. 1 comprises four side sections having respectively 40 the sheets 1, 2, 3, and 4 of side material conveniently gum veneer, secured to respective cleats 5, 6, 7, and 8 of any suitable wood. Preferably continuous binding wires 9 are secured to the side sections by staples 45 10, 10 which straddle the wires and pass through the side sheets into the cleats. Projecting ends 11, 11 of the wires are arranged to be twisted or otherwise secured together as shown at 11 in Fig. 3, thereby to complete 50 the continuity of the wire binding. As will be evident to those skilled in the art, it is not indispensable that the wire or other binding be applied in a continuous

length to an entire blank but it is preferred, where a binding means is employed, that it 55 encircle the box substantially continuously when the box is completely closed.

For the purposes of the specific illustrative box, the cleats are so proportioned relatively that they will meet in some such manner as that shown in Fig. 3; so that a group of cleats at each end of the box substantially close the end without necessitating the provision of any additional end pieces. With such an arrangement the cleated blank 60 65 may include in and of itself not only the box sides but also the box ends.

For the interfitting arrangement shown in Fig. 3, the cleats 6 and 8 are of the same length and are arranged to contact lengthwise when the blank is folded. The cleats 5 and 7 are of the same length, *i. e.*, a length equal to the combined widths of the cleats 6 and 8. With these four cleats 5, 6, 7, and 8 disposed as shown they completely or 70 75 substantially close and constitute the ends of the box.

It will be noted in the specific arrangement of Fig. 3 that the side sheets 2 and 4 at their lateral edges overlap the ends of the cleats 5 and 7 and also the edges of the side sheets 1 and 3 whereby the sheets 2 and 4 embrace between them the side section consisting of the sheet 3 and cleat 7 and also the side section comprising the sheet 1 and cleat 5.

According to a preferred method, a box embodying the features described may be made by forming four separate side sections laid out in some such manner as that indicated in Fig. 1, in which the sheet 1 has a width equal or substantially equal to the length of its cleat 5; the sheet 2 is sufficiently wide to provide at each edge an overlap margin 12 or 13 extending beyond the end 90 of the cleat 6, said overlap margin 12 being of a width substantially equal to the thickness of the sheet 1 and the width of the cleat 5 so that when the blank is folded the overlap margin 12 will extend as shown in Fig. 100 3. Likewise the overlap margin 13 is of a width preferably to overlap the adjacent end of the cleat 7 and edge of the sheet 3; and similar overlap margins 14 and 15 are preferably provided on the side section comprising the sheet 4 and cleat 8.

When the parts of the sections are assembled as a blank in such form as that shown in Fig. 1 the desired overlap margins for overlapping the cleat end by a sheet may be 5 provided by spacing one cleat from the next a distance not substantially less than the width of the cleat end to be overlapped; and to overlap one sheet edge by the margin of another sheet, the distance between cleats 10 may be increased by substantially the thickness of the side sheet to be overlapped. Thus, when a cleat for one section is spaced endwise from a cleat for the next section by a distance approximately equal to the width 15 of a cleat end to be overlapped plus the thickness of a sheet edge to be overlapped, the side sheet material may be assembled with the cleats so spaced in various ways so as to produce an overlap by one or the other 20 of the sheets as may be desired.

It is preferred that the side sheets be so related at their edges that the wires will be tensioned over the corner edges of the box when the box is folded; therefore, for example, it is preferred that the interval between 25 the edge of the sheet 1 to the edge of the sheet 2 be not greater than the thickness of the sheet 2 which is to overlap the edge of the sheet 1 in the folding. With this arrangement, when the edge of the sheet 1 is forced 30 under the margin of the sheet 2 and then forced into a position perpendicular to the sheet 2, the wire will be pulled over the corner so as to tension it strongly and perhaps to 35 cause the wire to embed itself to some extent in the corner of the sheet 2. This tensioning of the wire serves to hold the overlapping sheets securely tight and also to contribute to the stiffness and elasticity of the box. A 40 similar relation is preferably provided for between the right hand edge of sheet 2 in Fig. 1 and the adjacent edge of the sheet 3; and between the lefthand edge of the sheet 4 and the adjacent edge of the sheet 3; and 45 when the box is folded into the form shown in Fig. 3 and the ends 11 of the wires are twisted together, the wire may be thereby tensioned at all of the box corners.

It has been customary in wirebound 50 boxes heretofore made to provide end pieces to be inserted inside the cleats and to be secured to the cleats; but in the specific construction of box shown no end piece is necessary since the cleats, when arranged in 55 some such manner as that shown, sufficiently close the box ends. Thus, the entire box may be formed simply by forming a blank of separate side sections, folding the sections into box form and then completing 60 the continuity of the binding means so that the binding means may constitute alone the means for holding the parts together in box form.

A box embodying the features of this 65 invention may have a flexible character which

is extremely desirable. For instance, if the box of Fig. 3 is subjected to distorting forces acting in a diagonal direction, there may be a substantial tendency for adjacent edges of the side material to shift longitudinally relative to each other; and this shifting may occur without being substantially resisted except by the friction between the overlapping parts and the tensile strength of the binding wire. The wire or 70 other binding means is preferably laterally flexible to accommodate this longitudinal shifting of adjacent sheet edges. Hence the shifting may take place to a considerable extent without material danger of rupturing any of the parts and the extreme flexibility of the box is contributed to by the fact that, as illustrated in Fig. 3, each side section is wholly disconnected from adjacent side sections except by frictional contact and by the wire binding. For instance, if a distorting strain tended to shift longitudinally the edge of the sheet 3 in relation to the edges of the sheet 4, the cleat 7 and sheet 3 may slide relatively to the sheet 4 80 and its cleat 8 without material tendency to break any part and simply against the resistance of the frictional engagement between the parts and that resistance offered by the tensile strength of the binding wire. 90 While in some cases it may be preferable to provide for this maximum flexibility of the box by having the parts disconnected except by the wire, it would be entirely practicable to provide additional fastening means for 100 securing parts together to secure greater rigidity or for other reasons.

The described box, besides being flexible without material danger of breakage, is also desirably elastic in that when it has been 105 distorted, within reasonable limits, and the flexible wire and other parts have been thereby put under increased tension, they tend to restore themselves to their original box form.

It is to be understood that this invention is not limited to the particular construction, organization and method of manufacture hereinbefore described for illustration. On the contrary, the relations of the box parts 115 and the materials therefor may be variously modified in form and dimensions and the method of making the box modified in various particulars, all of which will appear to those skilled in the art. Furthermore, it 120 is not indispensable that all the features of the invention be used conjointly since they may be employed separately in combinations and sub-combinations defined in the following claims:

It is to be understood that the words "box," "ends," "sides," and similar words are employed herein as words of convenient designation and not words of limitation 130 since obviously the features of the invention

may be applied to other receptacles and containers than those ordinarily described by the word "box" (and which are intended to be included under that name as herein used); and it is immaterial what particular part of a box is employed in any given instance as its "end" or "side."

Claims.

1. A box comprising, in combination, ends including each four cleats, two of them substantially contacting lengthwise with each other, and the other two extending transversely of the first two cleats; material resting on said cleats and forming sides for the box; and binding wire secured to the side material parallel to the ends of the box.
2. A box comprising, in combination, ends including each four cleats, two of them substantially contacting lengthwise with each other, and the other two extending transversely of the first two cleats; material resting on said cleats and forming sides for the box; and binding wire secured to the side material and cleats and embracing the box ends.
3. A box comprising, in combination, ends including each a pair of long cleats substantially contacting lengthwise with each other; a pair of short cleats of a length approximately equal to the combined widths of said long cleats, and disposed across the opposite ends of said long cleats; and side material for said long cleats respectively disposed along their length and extending across the ends of the short cleats and providing an overlap margin beyond each short

cleat; and side material for each short cleat positioned between the overlap margins of the long sides; and bind-wires parallel to the box ends for securing the parts together. 40

4. A box comprising, in combination, ends including each a pair of long cleats substantially contacting lengthwise with each other; a pair of short cleats disposed transversely of said long cleats; and sides for 45 said long cleats respectively disposed along their length and across the ends of the short cleats and providing an overlap margin beyond each short cleat; and side material for each short cleat positioned between said 50 overlap margins of the long sides; and wire bindings embracing the box ends secured to the several sides and to each of said cleats.

5. A box blank consisting of separate box sections, each comprising side material and 55 cleats; two said sections being arranged to have their respective cleats contact longitudinally when folded; and the other two sections being arranged to interfit with the first two sections to substantially complete 60 the closures at the ends; and continuous wire bindings extending from end to end of the blank and secured to the cleats of the several sections.

In testimony whereof, I have signed my 65 name to this specification, in the presence of two subscribing witnesses.

OLIVER M. BABCOCK.
